UNITED STATES PATENT OFFICE.

GUSTAVE E. HUTTELMAYER, OF SCOTTDALE, PENNSYLVANIA.

SPOOLING DEVICE.

1,186,909.

Specification of Letters Patent. Patented June 13, 1916.

Application filed March 22, 1913. Serial No. 756,189.

To all whom it may concern:

Be it known that I, GUSTAVE E. HUTTELMAYER, a citizen of the United States, residing at Scottdale, in the county of Westmoreland and State of Pennsylvania, have invented certain new and useful Improvements in Spooling Devices, of which the following is a specification.

My invention has relation to mechanism 10 employed to regulate and control or guide ropes or cables in the coiling and uncoiling operations whereby the cables or ropes are wound or unwound upon the faces of cylindrical winding drums and while not 15 limited to such uses, more particularly relates to the construction and arrangement of a guiding or spooling mechanism whereby the course of the ropes or cables is directed during the winding and unwinding operations involved in coiling and uncoiling ropes 20 or cables wound upon the drums of mine hauls or mine hoists in a series of superposed layers or wraps.

Experience has demonstrated that a cable 25 or rope will not wind upon a drum in even layers or correct pitch, even when there is abundant lead (the distance from the drum to the nearest sheave wheel or equivalent fixed position of the rope). Upon beginning 30 to wind irregularly or get out of pitch, the ropes or cables build up irregularly upon the winding drums with the result that when under a strain or load, as is the case in the winding and unwinding operations, there is 35 great liability of the ropes or cables becoming broken, by reason of the great strains occasioned by the jerks resulting from the irregularly wound ropes or cables dropping from one to a lower level on the drums.

One object of my invention is to provide 40 a rope guide or spooling device having novel means whereby the rope or cable is evenly coiled upon the winding drum in a series of wraps or coils of uniform pitch.

Another object of the invention is to provide 45 a rope guide or spooling device having improved means by which the cable or rope is guided or controlled while being coiled upon the winding drum in a series of 50 superposed layers or coils of even or uniform pitch.

A further object of my invention is to provide 55 a rope guide or spooling device having a novel construction and arrangement of parts by the use of which a rope or cable is

caused to wind and unwind or coil and uncoil, and automatically travel across the face of the winding drum in alternately opposite directions during the winding and unwinding operations.

A still further object of this invention is to provide a rope guiding or spooling mechanism having improved means whereby the rope or cable is maintained under a uniform tension in winding and unwinding the cable 60 or rope on the drum.

Still further objects of the invention will appear hereinafter in the detailed description and appended claims.

Referring to the accompanying drawings 70 forming part of this specification, Figure 1 is an end elevation showing a spooling device, constructed and arranged and applied for use in connection with the winding drum of a mine shaft or mine hoist in accordance 75 with my invention. Fig. 2 is a plan of the apparatus of Fig. 1 showing the relative position of the spooling device and winding drum. Fig. 3 is a side elevation of the rope guide and guide operating mechanism forming 80 the spooling device comprising this invention. Fig. 4 is a sectional elevation showing a detail in the construction of the connection between the rope guide and guide actuating mechanism by which the rope 85 guide is reciprocated and controlled, in the winding operation.

In the accompanying drawings, the numeral 2 designates a rope winding drum secured on a drum shaft 3, the shaft being 90 rotatably mounted in suitable capped bearings 4, 4, in the usual known manner. The drum shaft 3 is connected by suitable slow-down gearing with a motor or other prime mover of any approved construction and the 95 drum and drum actuating mechanism, not forming part of this invention, are not further described. Positioned in front of the drum 2 at a suitable distance therefrom is the spooling device or rope guiding mechanism forming this invention.

As will be seen in Figs. 1, 2 and 3 a fabricated base for the spooling device is built up of beams 6, 6, and 7, 7, and is rigidly secured upon a suitable foundation 105 8. Separators 9 formed of channel beams are provided to secure the beams 7, 7, together, the beams and channels being riveted or otherwise secured together in assembled relation. Rigidly mounted upon 110

the so-formed base is a frame or housing 10, and on opposite ends of the housing are the pairs of capped bearings 11, 11, and 12, 12, by which the vertical shafts 13 and 14 are 5 rotatably mounted on the housing 10.

The vertical shaft 13 is provided at an intermediate point in its length with a bevel gear 15 which is keyed to the shaft and is positioned within the gap or throat 16 10 formed in the housing between the bearings 11, 11, and which meshes with the bevel pinion 17 on the end of the horizontal shaft 18, mounted in the bearings 19 and 20 on the beams 7, 7, forming part of the base 15 of the apparatus. The outer end of the horizontal shaft 18 is provided with a spur gear 21 which meshes with the spur pinion 22 keyed or otherwise fastened on one end of the horizontal shaft 23. The shaft 23 is 20 rotatably mounted in bearings 24, 24, which are bolted or otherwise secured in position on the web of one of the beams 7. Fastened to the other end of the shaft 23 is a sprocket chain wheel 25 which is connected by means 25 of a sprocket chain 26 (see Figs. 1 and 2) with a sprocket chain wheel 27 positioned on the drum shaft 3, so that when the drum and drum shaft are rotated the shafts 18 and 23 are actuated and caused to rotate 30 the vertical shaft 13 through the connecting bevel gears 15 and 17. The vertical shaft 13 mounted in the bearings 11, 11, and the vertical shaft 14 in the bearings 12, 12, each have a sprocket chain wheel 28 35 mounted on the upper end thereof and extending around these sprocket chain wheels 28 is an endless sprocket chain 29. Secured on opposite sides of the housing 10 at the ends of the base are brackets 30 by which 40 the horizontally extending ways or track rails 31, 31, are secured to the housing 9. The ways 31 are T-shaped in cross section and the horizontal leg of the T's is secured to the brackets 30. Mounted upon the horizontal track formed above the housing 10 45 by the ways 31 is a carriage having a frame 32 with grooved track wheels 33 arranged in pairs on opposite sides and at each end of the frame 32 so as to engage with the vertically extending legs 34 and 35 of the T-shaped ways 31, the lower wheels 33 preventing the carriage frame 32 from lifting or being raised from its track while being moved along the length of the track in the 50 rope guiding or spooling operations. Mounted in openings in the bosses 36, 36, on the carriage frame 32 are two vertical shafts 37, 37, the upper ends of these shafts engaging the bearings 38, 38, in the upper portion of the angular braces 39. The braces 39 extend downwardly and are secured to the ends of the carriage frame 32 so as to rigidly secure the shafts 37 in their upright position. The parallel vertically 55 extending shafts 37 each have an anti-friction

roller 40 rotatably mounted thereon and the rollers are spaced apart a sufficient distance to provide a lengthwise vertical gap 41 between the faces of the rollers 40 to permit the hoisting rope 42 to extend therethrough. In the middle of the length of the carriage frame 32 is a slot 43 extending lengthwise transversely of the width of the frame and movably mounted in this slot is a slide block 44 which reciprocates in the slot 43. The block 44 is provided with guide plates 45 and 46 which overlap and engage with the upper and lower faces of the frame 32 to maintain the block in position while being reciprocated in the slot 43. Rotatably secured in an opening in the slide block 44 is a pin 47 having a head 48 on its lower end and projecting outwardly from one side of the head 48 are lugs or ears 49 by which the pin 47 and slide block 44 are detachably secured to a link of the endless sprocket chain 29 extending around the sprocket wheels 28, 28, on the vertical shafts 13 and 14. 70 75 80 85 90

In the operation of my improved apparatus, the parts are assembled as is shown and has been described, with the hoist rope 42 extending through the slot 41 formed between the vertical guide rollers 40, 40, and secured by one end to the rope drum 2. 95

When the rope drum 2 is started to rotate, the sprocket wheels 27 on the drum shaft 2, through the sprocket chain 26 rotates the sprocket wheel shaft 18 on the spooling mechanism, and through the spur 100 pinion 22 on one end of this shaft 18 rotates the spur gear 21 and shaft 18, and, through the bevel gears 15 and 17 causes the vertical shaft 13 to rotate in the bearings 11. When this shaft 13 is rotated, the 105 sprocket wheel 28 on its upper end moves the endless sprocket chain 29 secured around this wheel 28 and opposite sprocket wheel 28 on the vertical shaft 14.

As the endless sprocket chain 29 moves 110 from one end toward the other of the track formed by the T-rails or ways 31, above the housing 10, the guide rollers 40, 40, are caused to move across the width of the face of the rope drum 2, at the same speed at 115 which the rope 42 is wrapped or laid on the rope drum. When the rotating drum 2 has been revolved a sufficient number of times to lay one layer of the rope 42 across its entire face, the carriage will have been moved 120 on its track exactly the same distance as the length of distance between the flanges on opposite ends of the rope drum, less the diameter of the rope 42. Further rotation of the rope drum 2 in the same direction 125 causes the rope to commence to form a second layer upon the drum and begin to wind upon the drum from the opposite end of the drum and the opposite hand, and in this movement also, of the drum 2, the rope 42 130

is guided and caused to become wrapped upon the drum in the desired uniform pitch by means of the guide rollers 40, 40, continued rotation of the rope drum 2 causing further movement of the endless sprocket chain 29 on the vertical shafts 13 and 14, and reversing the direction of movement of the carriage on its track at the proper time intervals.

10 At the beginning of the movement which causes the second layer to be formed on the rope drum the slide block 44 will have moved from one end to the other of the slot 43 in which it is mounted and will begin 15 to move in the opposite direction, the pin 47 connecting with the endless chain 29 moving on the opposite side of a line drawn through the center of the vertical shafts 13 and 14 during such movement of the carriage and rope guiding rollers.

20 The above described operations are then repeated with each successive pair of layers of the rope laid upon the rope drum in the hoisting operation, the carriage being reciprocated on its track and the length of travel of the carriage being equal to the distance between the flanges on the opposite ends of the rope drum 2, so that when the rope drum is rotated the number of revolutions necessary to lay a complete layer 30 of the rope thereon, the carriage will be automatically caused to change its direction of movement and reverse the direction.

25 In unwinding the rope from the drum the same cycle of operations is carried out, the guiding rollers reciprocating back and forth from one end to the other of the drum in the same manner as when coiling the rope upon the drum.

35 40 The advantages of my invention will be apparent to those skilled in the art. By the use of my improved spooling device the ropes or cables are evenly laid upon the winding drums, the liability of breakage of 45 the ropes and consequent damage and expense being very materially reduced.

Modifications in the construction and arrangement of the parts may be made with-

out departing from my invention as defined in the appended claims. 50

I claim:

1. In a spooling device for rope winding drums, the combination of a horizontally reciprocating carriage movable across the face of the winding drum, said carriage having upwardly extending axially vertical rollers forming a rope guide, a support for said carriage, said carriage having anti-friction wheels engaging the upper and lower surfaces of the carriage support and means connecting the carriage and drum for positively reciprocating the carriage when said rope drum is rotated. 55

2. In a spooling device for rope winding drums, the combination of a horizontally reciprocating carriage movable across the face of the winding drum, said carriage having upwardly extending axially vertical rollers forming a rope guide, a support for said carriage, sprocket wheels on the support having an endless carriage operating sprocket chain thereon, said chain being pivotally connected to the carriage, and means operatively connecting one sprocket wheel to the winding drum shaft whereby the carriage is positively reciprocated when said rope drum is rotated. 60

3. In a spooling device for rope winding drums, the combination of a horizontally reciprocating carriage movable across the face of the winding drum, said carriage having upwardly extending axially vertical rollers forming a rope guide, a support for said carriage, means on the carriage engaging the lower side of the carriage support to prevent tilting of said carriage, and mechanism operatively connecting the carriage and drum operating mechanism for positively reciprocating the carriage when the rope drum is rotated. 65

90 In testimony whereof, I have hereunto set my hand.

GUSTAVE E. HUTTELMAIER.
